Sam'l. Knight

United States Patent Office.

ROBERT HAMILTON, OF FRANKLIN, INDIANA.

Letters Patent No. 98,957, dated January 18, 1870.

IMPROVEMENT IN ROAD-SCRAPERS.

The Schedule referred to in these Letters Patent and making part of the same.

I, ROBERT HAMILTON, of Franklin, in the county of Johnson, and State of Indiana, have invented a certain Road-Scoop or Scraper, of which the following is a specification.

My invention relates to certain improvements in the road-scraper, patented to me on the 26th day of January, 1869; and

The first part of my invention consists in a device for insuring greater stiffness and stability in the frame.

The second part of my invention consists in an improved construction of spring-latch, whereby it is adapted for use, either by the hand or by the foot, at will.

Figure 1 is a side elevation of a scraper embodying my invention, one of the handles being broken off, and the scoop being shown in section.

Figure 2 is a perspective view of the same, with the scoop disengaged.

The beam A, handles B B', and braces C C' of my improved implement, are of iron, the beam being curved downward and forward, as shown, so as to dispense with a sheth, and, in conjunction with the said iron handles and braces, to constitute a frame-work which combines strength with lightness.

The lower end of the beam A terminates in a T-head, K, whose extremities enter ears E E', on the under side of the scoop D, so as to constitute a hinged connection between the frame and scoop.

Braces F F', extending obliquely rearward from the extremities of the T-head K to the beam, serve to stiffen and preserve the parts in their proper relative positions.

When in use, the rear portion of the implement rests upon a shoe, G.

The open movement of the scoop D is restricted by a chain, H, as in my patent aforesaid.

The different parts of the implement are united by bolts L and nuts l, the removal of which will permit the detachment of any member of the frame-work in case a portion should become broken. The nuts l being of a uniform size, can all be operated by a single wrench, which may be furnished with the implement.

The scoop is caught and held to its effective position by a spring-latch, I, which is capable of being operated by the foot, as in my aforesaid patent, but is also provided with a hand-trigger, J, whereby the operator is enabled to liberate the scoop by means of his right hand, without letting go of the handle, it being found that one liberating-device is more convenient to one operator, and the other to another.

The lower end of the beam enters a recess in the shoe G, and is secured therein by traversing bolts.

I claim, as my invention—

1. In the described combination with a beam, A, handles B B', braces C C', and pivoted scoop D, constructed as represented and described, the T-head K, ears E E', and braces F F', constructed, arranged, and employed as set forth for the purpose shown.

2. In combination with a pivoted scoop, D, the spring-latch I J, adapted for operation by foot or hand, as and for the purpose specified.

3. The combined arrangement of the beam A, handles B B', pivoted scoop D E E', shoe G, T-head K, braces C C' F F', chain H, spring-latch I J, and fastenings L l, constructed and employed as described, as and for the purpose set forth.

In testimony of which invention, I hereunto set my hand.

ROBERT HAMILTON.
